UNITED STATES PATENT OFFICE.

EDWARD E. GOLD, OF NEW YORK, N. Y.

STEAM-TRAP.

SPECIFICATION forming part of Letters Patent No. 398,719, dated February 26, 1889.

Application filed January 27, 1888. Serial No. 262,122. (No model.)

To all whom it may concern:

Be it known that I, EDWARD E. GOLD, of New York city, county and State of New York, have invented certain new and useful Improvements in Trap-Valves for Steam-Heating Systems, of which the following is a specification.

This invention relates to valves in the nature of steam-traps or drainage or relief valves applicable to steam-heating systems, and designed especially for use with the steam-heating pipes of railway-cars.

In the heating of railway-cars by steam difficulty has been experienced on account of the liability of water of condensation being left in the pipes and freezing there in cold weather. In the well-known Gold system of car-heating the steam-pipes by which steam from the locomotive is conducted to the cars are provided with thermostatic traps, which remain closed by the expansion of an elastic vessel so long as this vessel is heated by the presence of steam in the pipes, and open automatically by the contraction of the vessel when the pipes are cooled and the steam is condensed. The thermostatic trap being arranged at the lowest point of the steam-pipe, the water of condensation is thus automatically drained out. This thermostatic trap is illustrated in my patent, No. 350,880, dated October 12, 1886. In the development of the Gold heating system traps of this character are applied in various locations in connection with the main and branch steam-pipes and at the terminals of the pipes or chambers supplying hot water or liquid radiators. In my patent, No. 392,424, dated November 6, 1888, I have illustrated this thermostatic trap as applied to the bowls or chambers of the hose couplings by which the connection is made between the steam-pipes of successive cars of the train. As the coupling is ordinarily the lowest point in the system of steam-pipes, the arrangement of the thermostatic trap at that point enables the water of condensation to be freely drained from the entire system of pipes.

Difficulty has been experienced in the use of thermostatic traps for draining the steam-heating pipes, because of the liability that the condensation of the steam shall create a vacuum in the pipes which may be sufficient to hold the thermostatic trap-valves closed by

suction, thereby retaining the water of condensation in the pipes, where it may freeze. My present invention is designed, in part, to overcome this difficulty, and provides a means of either dispensing entirely with thermostatic valves or of so coupling the thermostatic expansion device that its action shall not be defeated by the formation of a vacuum in the pipes. To this end I provide the system of steam pipes or vessels with a drainage or relief valve or valves situated, preferably, at the lowest point or points in the system, in order to be effective in draining away the water of condensation, which valve is constructed to open inwardly, and is provided with a spring or other equivalent tension device acting to unseat or open the valve, but having a tension insufficient to resist the steam-pressure normally employed in the pipe or vessel, so that while the steam-pressure continues the valve is held closed; but upon the cessation of the steam-pressure and before the formation of the vacuum the valve will be automatically opened and will permit the water of condensation which has accumulated above it to escape. As an accessory to this automatic valve, and in order to insure that it shall properly close when the steam is turned on, and that it shall close even with a less pressure of steam than would be sufficient to overcome the tension of its spring, I provide a thermostatic expansion device arranged within the steam pipe or chamber and connected to the valve in such manner that when it expands by the heat of the steam it will force the valve to its seat. To enable this connection to be properly adjusted, I provide suitable adjusting stops or screws for regulating the position of the thermostatic device relatively to the valve. As a further accessory to the automatic valve, I provide a screw or equivalent device, by means of which the valve may at any time by manipulation be forced to its seat, and thereby rendered inactive. Such a device will be useful in case the valve should get out of order or in any manner become inoperative, or in case it should be desired to render the valve inoperative—as, for example, if it became necessary to operate the heating apparatus with a lower pressure of steam than that to which the valves may be adjusted, in which case in the absence

of means for manually closing the valves they would remain open and permit the steam to escape and go to waste. In case, also, for example, a train is to be heated by exhaust-steam 5 from the engine, it will be necessary to thus close the valves manually.

I apply my improved valve or trap, by preference, to the couplings, as these are usually the lowest points in the system of heating- 10 pipes and the ones toward which the water of condensation will usually drain. When applied to the coupling, my present invention supersedes the thermostatic trap heretofore applied thereto and obviates the necessity of 15 forming the coupling bowls or heads with pendent chambers projecting below them, as heretofore. When the thermo-expansive vessel is employed, it is placed within the chamber in the coupling-head or in a recess at the 20 upper side thereof.

Figure 1 of the accompanying drawings is a side elevation, on a reduced scale, of the flexible hose and coupling for connecting together the steam-heating pipes of two adjoining cars of a railway-train, a fragment of the main steam-pipe on one car being shown. Fig. 2 is a vertical longitudinal mid-section of one of the coupling heads or bowls on a larger scale. Fig. 3 is an elevation of the construction of valve shown in Fig. 2, removed from the coupling. Fig. 4 is a similar section to Fig. 2, showing a modified construction. Fig. 5 is an elevation of a portion of one of the liquid-heating vessels or radiators within the car employed in my system of heating, partly in vertical mid-section, and illustrating the application of my present invention thereto. Fig. 6 is a fragmentary vertical section, on a larger scale, of the lower portion of the steam 35 or drip pipe shown in Fig. 5. Fig. 7 is a transverse section cut on the line 7-7 in Fig. 6. Fig. 8 is a vertical transverse section of the coupling-head, cut on the line 8-8 in Fig. 1, and showing a modified construction. Figs. 9, 10, and 40 45 11 are longitudinal mid-sections of coupling-heads similar to Figs. 2 and 4, and showing three different modified constructions.

I will proceed to describe my invention as applied to the Gold system of car-heating, and 50 with special reference to the particular system or arrangement wherein the main steam-pipe is divided into two branches, which extend through the car along opposite sides thereof and at the farther end are reunited, and within 55 the car is arranged a water or other liquid heating and radiating circuit.

Referring to Fig. 1 of the accompanying drawings, let A designate the main steam supply or heating pipe of a car, B the flexible 60 hose connected to the end of the pipe A, and C the coupling by which the terminal end of the hose B is connected to the corresponding end of the hose of the adjoining car. In the particular construction here shown the hose 65 B is connected with the steam-pipe A in permanent manner by means of a coupling clamp or sleeve, a, and at its other end it is con-

nected by similar means to the neck of one of the interlocked halves or heads of the coupling C. This coupling is or may be in the 70 main of the same construction as illustrated in my said patent, No. 392,424, to which reference is made for a more particular description of the mechanical provisions by which the two heads of the coupling are interlocked. 75 Suffice it here to say that each coupling-head is formed with an angular trunnion-arm adapted to embrace the opposite head, and with inclines or wedging-surfaces acting against said trunnion-arms, which force the two halves firmly together as they are turned on each other in the dropping of the coupling and hose into their usual drooped or sagging position, as shown. The main steam-pipe A is preferably provided near its end with a 85 stop-cock, b.

Fig. 5 of the accompanying drawings shows a heat-storage radiator, G, consisting of a vessel containing water, brine, or other suitable liquid, and connected by the pipe r to the 90 next vessel in the liquid-heating circuit, and the corrugated pipe n, being a branch steam-pipe leading from the main pipe A, which extends through the vessel G and terminates at its end remote from the steam-pipe in a pipe, 95 o, leading to a steam-trap, p, from which a drip-pipe, p', descends through the floor of the car in order to discharge the water of condensation upon the track.

m is the liquid-space within the vessel G. 100

I will now proceed to describe my present invention with reference first to the preferred construction thereof shown in Figs. 1 and 2, wherein it is illustrated as applied to the coupling C. 105

Each coupling head or bowl D is formed, as usual, with a short cylindrical chamber, and in this chamber is placed the improved trap or drainage-valve provided by my invention, and which, as a whole, is designated by the 110 letter E. This trap is shown in Fig. 3 removed from the coupling. It is constructed with a valve-seat, c, which is screwed into a boss formed on the underside of the coupling-head, and has a head or flange, d, preferably 115 hexagonal, which comes against the boss with an intervening packing.

Through the seat c is formed an outlet-opening, e. The valve F is mounted on a valve-stem, f, which is suitably guided and 120 receives the upward tension of a spiral spring, g, which tends to lift the valve F off from its seat. When the steam-pressure is turned on, it forces the valve down against the tension of the spring and closes the outlet. 125

The valve-seat c is formed at the lowest point in the coupling-head when the latter is in the position normally assumed by it in use, in order that all the water of condensation may be drained out when the valve is 130 opened. The valve F is preferably provided with a packing-ring, h, of Jenkins's composition, in order to cushion in yielding manner against the seat and make a tight connection.

In the preferred construction the valve-stem is guided by means of a tubular frame or standard, *i*, forming part of the valve-seat *c*. A washer, *j*, is dropped into this tubular frame or standard and rests against a ledge or shoulder, *k*. A spring, *g*, rests upon this washer, and a nut, *l*, is screwed upon the stem *f* and receives the upward tension of the spring, this tension being adjustable by screwing the nut up or down on the stem. The valve-stem is guided at its lower end by the central hole in the washer *j* and at its upper portion by the nut *l*, which has wings or arms projecting from it and terminating against the inner walls of the standard *i*. The washer *j* forms a stop for limiting the upward movement of the valve *F*, the upper side of which abuts against the lower side of the washer, as shown in Fig. 2. When the valve is lifted, the water of condensation flows out through openings *q q* in the standard *i* above the valve-seat *c*.

Just above the upper end of the valve-stem *f* is arranged a thermostatic expansion device, *H*. The particular description of this device which is here shown consists of a vessel or chamber some portion of which, preferably the lower side, or the whole vessel, is sufficiently elastic to expand under the tension of an internal pressure, and in this vessel is placed a quantity of a volatile liquid, which volatilizes at a temperature below that of steam—such, for instance, as alcohol. When steam is turned on, it heats the liquid in the vessel *H* and expands the latter. The vessel *H* is so arranged that when it thus expands it will come in contact with the upper end of the valve-stem *f* and exert a downward pressure thereagainst, thereby forcing the valve *F* down to its seat in case it has not yet been seated by the direct pressure of the steam. To accomplish this result, it is important that the vessel *H* shall be constructed to expand to an extent at least equal to the lift of the valve *F*, and that it shall stand at the proper height relatively to the valve-stem *f*. The latter requisite is effected by any suitable adjusting devices, preferably adjusting-screws, which may be set once for all to the proper position. The screws *s s* in Fig. 2 are provided for this purpose, as by screwing them up or down the thermo-expansive vessel *H* will be brought to a higher or lower position. The vessel *H* is fastened to the lower end of a screw, *I*, which turns in female threads in a cap, *J*, which closes the opening in the top of the coupling-head *D*, through which the vessel *H* is inserted therein. A stuffing-box, *t*, is provided to pack the screw *I* against leakage.

The screw *I* is provided with a T-head, *I'*, at its upper end, or with a hand-wheel, or with a squared end that may be engaged by a wrench, or is constructed in any manner so that it may be turned in order to move the thermo-expansion vessel *H* up or down. The

screws *s s* form merely stops to limit the upward movement of the vessel *H*, which ordinarily is lifted by the screw *I* until it is in firm contact with these stops, at which time 70 it should be in proper adjustment relatively to the valve-stem *f*, so that when the vessel is expanded by heat it will press down the valve-stem and seat the valve.

The function of the thermo-expansion device *H* is to insure the seating of the valve in case it should not be properly seated by the steam-pressure. This might occur in consequence of imperfect fitting of the working parts of the valve *E*, or of corrosion thereof, 80 so that they do not work freely, or in consequence of obstructions in the nature of sediment which might find their way beneath the valve *F*; or the failure of the valve to be seated by pressure might be due to the adjustment of the spring *g*, being at too great a tension for the steam-pressure used for the time being, in which case the steam, even at low pressure, being sufficient to heat and expand the vessel *H*, would insure the proper 90 closing of the valve. The expansion of the vessel *H* exerts considerable force, sufficient to press the valve *F* to its seat against any resistance that may ordinarily oppose it, and even against any ordinary obstructions 95 beneath the valve.

It is desirable at times to be able to close by manual means any automatically-operated valve of this character, either in consequence of the valve becoming inoperative through derangement or when the apparatus is to work under unusual conditions. For example, in case the cars are to be heated by exhaust-steam instead of by live steam, it would be desirable to close manually all of the traps, 100 in order that there should be no waste of steam by its escape through them, its pressure being insufficient to close the valves, and it being in such case undesirable to rely upon its heat causing the closure of the valves 105 through the action of the thermo-expansion vessels. To provide for this is the function of the screw *I*. When it is desired to close the valve, the screw *I* is screwed down; thereby lowering the vessel *H* against the valve-stem *f* and pressing the valve down to its seat. 115

In order to prevent a careless train-hand from injuring the vessel *H* by screwing down the screw *I* too hard, a block or buffer, *u*, may be placed inside the vessel, being fastened to the end of the screw *I* and extending down nearly to the flexible diaphragm forming the bottom of the vessel, in order that when the parts are screwed down so firmly that this diaphragm is pressed upwardly by the end 120 of the valve-stem *f* it shall be re-enforced against the lower end of the block *u*. When it is desired to restore the valve to its normal condition, the screw *I* is to be screwed up until stopped by the abutment of the vessel *H* against the stop-screws *s*. The upper 130 side of the vessel *H* may be made of thick

material in order to resist the strain which may be occasioned by screwing up the screw I too forcibly.

My present invention combines the advantages of a thermostatic trap with those of a trap operating solely by the pressure of the steam. The disadvantage of a thermostatic trap that the existence of a vacuum within the pipes will prevent its opening is overcome in this construction, since the expansion-vessel H does not come directly against the valve-seat, and consequently suction has no power to retain the valve closed. The vessel H is surrounded on all sides by the fluid medium within the coupling-head, and consequently is balanced in so far as any tendency exists to move it bodily toward or from the valve-seat. The only tendency of a vacuum would be to expand the vessel H; but as a vacuum only occurs at a low temperature the contractile tendency of the vessel will be greater than the expansive tendency due to the vacuum around it, and hence it will not remain expanded, and will not act to retain the valve closed and prevent the escape of the water of condensation.

My invention also combines the advantages of an automatic and a manually-operated drainage valve or cock, in that it may be instantaneously converted from one to the other.

My invention may be modified in various ways without departing from its essential features. For example, the means for manually closing the valve may be omitted in any case where it is considered that an automatic valve can be relied upon, and the thermostatic device for insuring the closing of the valve may be omitted whenever high steam pressures are to be used exclusively. The construction of the valve itself may be varied in many ways; and the retractile device by which it is given a tendency to open may be either a spring or a weight, or any equivalent thereof.

My improved valve may be applied either at the coupling or at any other part of the heating system wherever water of condensation is liable to accumulate and requires to be drained off.

Fig. 4 shows a modification which is distinguished chiefly by the omission of the screw I for manually closing the valve, and by the omission of the screw-stops s s for adjusting the height of the thermo-expansive vessel H. This vessel is dropped into a recess in the top of the coupling-head D, and rests on a ledge or flange, v. If it requires adjustment up or down, this is accomplished by inserting a washer, w, of greater or less thickness beneath it. The cap J is screwed in above the vessel H to close the top of the chamber which it occupies. In order that steam may be admitted to all sides of the vessel H, a chamber or space is formed above it and around it, and steam-channels x x are formed to admit the steam to the surrounding space. The valve

F is shown in this view as being formed with a conical face fitting against a coned seat. In other respects the construction is the same as that first described.

Fig. 5 shows not only the application of my improved trap-valve in another part of the heating system, but also illustrates some modifications of construction. The trap is here employed at the termination of one of the branch steam-pipes, into which steam is admitted from the main pipe in order to heat the liquid in the heater G. The short section of pipe o, which terminates this branch steam-pipe, is screwed into the casing of the trap p, which is formed with a chamber, D', above, in which is arranged the thermo-expansion vessel H, and from the bottom of this chamber a pipe, p', extends downward beneath the floor of the car and terminates in the drainage-trap E. This trap E and the expansion-vessel H are arranged at a considerable distance apart, a long stem or rod, f', being employed to make connection between them, this stem extending through the center of the pipe p'. The vessel H is adjusted up and down by a screw-stem, I, working through a stuffing-box, t, at the top of the chamber D'.

The construction of the trap E is shown in Figs. 6 and 7, where it is seen that a block, K, is screwed into the lower end of the pipe p'. This block is formed with the valve-seat c, and has a flange, d, which abuts against the end of the pipe. The valve F has its stem f passing downwardly through the valve-seat, guided by three wings, y y, as shown in Fig. 7, with a cap-nut, j', screwed on its lower end and forming a stop, which, striking against the lower ends of the wings, limits the upward movement of the valve.

The tension device for lifting the valve consists in this construction of a weight, W, in lieu of a spring. This weight is formed or mounted on one arm of a lever, L, which is fulcrumed on a screw, z, in the block K, and the opposite end of which takes under the cap-nut, j'. The rod f', by which connection is made between the expansion-vessel H and the valve, is fastened at its upper end to the vessel H, as shown in Fig. 5, and at its lower end is guided by wings w', Fig. 6, in order to maintain it centrally within the pipe p', and its bottom extremity stands just above the valve F. The adjustments and proportions are such that the expansion of the vessel H when steam is turned on will lower the rod f' sufficiently to cause its bottom end to strike the valve F and press the latter down to its seat. This construction of a weight-retracted valve is illustrated here merely to show a modification of which my invention is susceptible, the construction first described being preferred.

In Fig. 8 is shown a modification of the connection between the expansion-vessel H and the valve F, which are otherwise constructed substantially as shown in Fig. 4. The vessel H, instead of being placed in a horizontal

plane above the valve, is arranged in a vertical plane at one side thereof and against the side wall, C', of the coupling-head D. This arrangement permits a vessel H of larger diameter to be used without necessitating any widening of the coupling-head or other change in its shape. The vessel H is held against the wall C' by a skeleton thimble, N, which is passed into the chamber of the coupling-head through the side thereof, on which is formed the valve-seat for connection with the opposite coupling, a sufficiently large opening being provided for the purpose, which is afterward closed by the screwing in of an annular cap or collar, M, which carries the valve-seat, and which, as it is screwed home, clamps the thimble N in place. This thimble is made in skeleton form, in order not to obstruct the opening B', through which the steam enters from the hose B, and in order to permit the trap E to be screwed in from below, this trap is constructed in substantially the same manner as in Fig. 4, except that its stem f does not project so high, stopping short somewhat below the center of the coupling-head. The movement due to the expansion of the vessel H is communicated to the stem f through the medium of an elbow-lever, Q, as clearly shown. The necessary adjustment of this lever relatively to the stem f may be effected by lengthening or shortening the stem by screwing it up or down in the valve F and securing it by a set-nut, b'.

Fig. 9 shows a construction wherein the thermo-expansion vessel or device H is wholly omitted. The trap E is of the same construction as in Fig. 1, and a screw, I, is provided, screwing in a cap or block, J, at the top of the coupling-head and packed by a stuffing-box, t. By screwing down this screw the valve F will be forced to its seat, and thereby closed manually.

Fig. 10 shows a modified construction wherein the trap E, which is constructed the same as in Fig. 4, is wholly unprovided with any means of manually closing it—a construction which may be preferred in some instances.

In all of the constructions thus far described wherein a spring, g, is employed as the tension device for lifting the valve this spring has been arranged above the valve, where it is out of the way of the outflowing stream of liquid.

In Fig. 11 I have shown a modified construction wherein the spring g is arranged beneath the valve and in the outflow-passage. The valve F is here at the highest point, its stem f extending thence downwardly through the tube i, and being guided by a hub or spider, j, cast or otherwise secured within this tube, and which thus forms a reinforcement for the spring g, which bears upwardly against the valve F. On the lower end of the valve-stem is screwed a winged nut, l, the arms of which work in an enlarged or counterbored portion of the tube i, in order to guide the

stem f and form a stop to limit the upward movement thereof by their abutment against a shoulder, k'.

It will be understood that in lieu of the thermo-expansion vessel H, which is in itself an old and well-known construction of thermo-expansion device or thermostat, I may use any other thermo-expansion device which is capable of operating in an equivalent manner in order to force the drainage-valve to its seat when heated by the presence of steam.

It is to be understood that although I have described my present invention with special reference to its applicability to the Gold system of heating railway-cars by steam, yet it may be applied to other systems of heating, such as are already known.

My invention is not limited in its application to heating systems for cars, but is applicable also to systems of heating for houses or apartments, and also to steam-pipes or steam-vessels generally, including those used for other purposes than steam-heating.

I claim as my invention the following defined novel features, substantially as hereinbefore specified, viz:

1. The combination, with a steam-heating system, of an automatic trap consisting of a drainage-valve connected with the steam-heating pipe or vessel and opening inwardly, and a tension device arranged to exert a pressure against said valve tending to open it, but insufficient to resist the normal steam-pressure in said pipe or vessel, whereby said valve is closed when steam is turned on and opens automatically when the steam-pressure ceases.

2. The combination, with a steam-pipe coupling for the steam-heating pipes of a railway-car, of an automatic trap applied to the coupling-head, consisting of a valve opening inwardly, with its seat arranged to drain the liquid from the normally-lowest portion thereof, and a tension device arranged to exert a pressure against said valve tending to open it, but insufficient to resist the normal steam-pressure within the pipes.

3. The combination, with a steam-pipe coupling for the steam-heating pipes of a railway-car, of an automatic trap applied to the coupling-head, consisting of a valve-seat at the normally-lowest part of the head, a valve opening inwardly from said seat, a retracting-spring tending to open the valve, but insufficient to resist the normal steam-pressure, a valve-stem, guides for said stem, and a stop for limiting the opening movement of the valve.

4. The combination, with a steam-heating system, of an automatic trap consisting of a drainage-valve connected with the steam-heating pipe or vessel and opening inwardly, and a tension device arranged to exert a pressure against said valve tending to open it, but insufficient to resist the normal steam-pressure in said pipe or vessel, and a screw

- arranged when turned to force said valve to its seat, whereby the automatic operation of the valve may be prevented at will. 30
5. The combination, with a steam pipe or vessel, of an automatic trap consisting of a valve-seat, a tubular standard borne by said seat, a valve opening inwardly, a valve-stem within said standard, a transverse partition in said standard forming a stop for limiting the opening movement of the valve, a spring tending to open the valve re-enforced against said partition, and an adjusting-nut screwing on the valve-stem and receiving the tension of said spring, whereby the latter may be 35 adjusted. 40
6. The combination, with a steam pipe or vessel, of an automatic trap consisting of a valve-seat, a tubular standard connected thereto and formed with an internal ledge or shoulder, a washer or disk placed within said standard against said shoulder, a valve opening inwardly, a valve-stem fixed to said valve and extending axially through said standard, a guiding-nut screwed on said valve-stem, and a spring tending to lift said valve re-enforced 45 against said washer and reacting against said guiding-nut. 50
7. An automatic trap consisting of a valve opening inwardly and a tension device tend-
- ing to open said valve, combined with a thermo-expansive device arranged relatively to said trap, so that upon its expansion by heat its movement shall be communicated to and shall close said valve, an adjustable stop to limit the movement of said expansion device 35 away from said valve, and a screw connected to said thermo-expansive device and adapted to move the latter toward or from the valve, whereby by turning said screw the valve may be forced to its seat. 40
8. A hose-coupling head formed with a circular opening in its upper side, a cap closing said opening, a thermo-expansive vessel within the chamber of the coupling-head, a screw passing through said cap for vertically 45 adjusting said vessel, and an automatic trap within the chamber of the coupling-head, consisting of a seat at the normally-lower side thereof, a valve opening inwardly and arranged relatively to said thermo-expansive vessel, so that the expansion of the latter will force it to its seat, and a tension device arranged to exert a pressure tending to open said valve. 50

EDWARD E. GOLD.
